UNITED STATES PATENT OFFICE.

GEORGE E. NORRIS, OF TROY, ASSIGNOR OF ONE-HALF TO JAMES K. P. PINE, OF LANSINGBURG, NEW YORK.

STAYING-PIECE FOR GARMENTS.

SPECIFICATION forming part of Letters Patent No. 295,935, dated April 1, 1884.

Application filed June 20, 1883. (No model.)

To all whom it may concern:

Be it known that I, GEORGE E. NORRIS, of the city of Troy, county of Rensselaer, and State of New York, have invented a new and useful Improvement in Staying-Pieces for Garment-Slit Openings, of which the following is a specification.

My invention relates to certain improvements in the manner of making and applying the staying-pieces used upon the back opening and sleeve-opening of shirts, and the side openings of drawers and overalls, as well as the front openings in the latter.

My invention consists, as will hereinafter be more fully detailed, in the combination, with a staying-piece attached to one side of the garment-slit, of a corded edge upon the subtending edge of the fly, and the latter and a corded edge upon the strip forming the fly, and an underlap made with a strip and combined corded edge where coincident with the closing edge of the fly.

In the accompanying drawings, forming a part of this specification, there are shown two figures illustrating parts of a shirt containing my invention, and in both of which the same designation of parts by letter-reference is used.

Figure 1 shows a plan view of a shirt-back opening containing my invention, with the part of the shirt thereto adjacent. Fig. 2 illustrates a vertical section of the parts, taken on the line $x'x'$ of Fig. 1, with the relative thickness of the material exaggerated, to better illustrate them.

The several parts of the shirt and the combined and corded staying-pieces are designated by letter-reference, and the manner of attaching them is described as follows:

The letter A' indicates a rectangular strip of material used to produce the overlap or fly. It has a uniform width throughout its length, excepting at the bottom below the slit, where it is made pointed. This strip A', as indicated at Fig. 2, is on one of its edges sewed to one side of the slit, as indicated at S', by a line of stitching, O'. It is then turned over and down and folded at B, to receive the cord C', then frontwardly folded over and past the attached edge of the slit S', so as to cover the latter and attach to the shirt-body S² at d, with

the exterior edge of the strip corded at C². The underlap is made of a strip of material, A², having a uniform width, and which, as indicated at Fig. 2, is on one of its edges attached to the underlap edge of the slit S². It is then turned over and down longitudinally and frontwardly, is corded at C³ on its lapping edge, and inside of the latter is sewed to the shirt-body S² at O². At the bottom, as indicated at O⁴, the piece A² is transversely sewed to the piece A', as designated at O⁴.

While I have shown the strip A' as corded on its edge where attached to the shirt-body, as well as on its fly-edge, the corded of said strip where joined to the shirt-body may be omitted, if desired, and the strip attached without the cord at that point, the corded upon the fly-edge of the strip A' being retained.

Thus made and applied, a substantial attachment is produced to secure the parts, and a superior finish given to the shirt at that point.

Having thus described my invention, what I claim, and desire to secure by Letters Patent, is—

1. In an overlapping fly for a garment-slit opening, the combination of a strip having a uniform width for attachment to the slit, and which strip is sewed on one of its edges to one edge of the slit reversely placed, is then turned over and down frontwardly, and longitudinally folded to produce a fly-edge subtending the slit, with the other edge of the strip sewed to the shirt-body exteriorly, so as to cover and subtend the inner union of the strip and slit, and a corded edge upon the subtending vertical edge of the fly, as shown and described. 75

2. In an overlapping fly for a garment-slit opening, the combination of a strip having a uniform width for attachment to the slit, and which strip is sewed on one of its edges to one edge of the slit reversely placed, is then turned over and down frontwardly, and longitudinally folded to produce a fly-edge that subtends the slit, with the other edge of the strip sewed to the shirt-body exteriorly, so as to cover and subtend the inner union of the strip and slit, a corded edge upon the fly, and a corded edge upon the exterior of the strip where attached to the shirt-body, as shown and described. 100

3. In an underlap for a garment-slit opening, the combination of a strip of uniform width reversely placed with reference to the edge of the slit beneath the fly, and sewed thereto, turned over and down outwardly and forwardly, and on its outer edge attached to the shirt-body and corded, as shown and described.
4. In combination with a garment-slit opening, an overlap or fly made from a strip of material that is on one of its edges, as shown, attached to one edge of the garment-slit, and on its other edge exteriorly attached to the shirt-body, to subtend the inner union of the strip and slit, and where folded longitudinally to oppositely subtend the slit and produce the

fly, a corded edge on fly and strip, an underlap made of a strip that on one edge is sewed to the edge of the slit, as shown, and folded over and down exteriorly, and on its outer edge attached to the shirt-body, with its lower end transversely sewed to the overlap, and the outer edge of the piece forming the underlap corded, as herein described. 20

Signed at Troy, New York, this 8th day of 25 June, 1883, in the presence of the two witnesses whose names are hereto by them attached.

GEO. E. NORRIS.
